NIKLAUS MEIER, OF LUCERNE, SWITZERLAND.

TYPE COMPOSING AND CASTING MACHINE.

Application filed July 3, 1922. Serial No. 572,412.

To all whom it may concern:

Be it known that I, NIKLAUS MEIER, a citizen of the Swiss Confederation, residing at Lucerne, Switzerland, have invented 5 certain new and useful Improvements in Type Composing and Casting Machines, of which the following is a specification.

With the type casting and composing machines of known construction designed for 10 the production of justified lines composed of single types the matrices are mounted singly or in groups upon rods, disks, rings, plates, chains or the like. With all these devices the matrices have to travel to the 15 casting mould over distances of different lengths wherefrom results that if the direct casting has to be effected by the depression of the key the manipulation of the keys is effected at irregular speed.

20 In the type casting and composing machine which forms the object of the invention the matrices are mounted upon oscillating levers and they are conveyed to the common casting mould by the depression 25 of keys, so that owing to the lever striking upon the casting mould the matrix is centered in the casting mould and jammed in the same, whereupon the type is cast and, 30 during the time the matrix lever is returning to the initial position, the cast type is conducted along knives to the line to be composed and added to the same. By the depression of a corresponding key provisional spacers are inserted in the line which 35 are finally replaced by definite cast pieces which in being inserted in the line push the corresponding provisional spacers back into the magazine.

In order that the invention may be clearly 40 understood, I shall proceed to describe the same with reference to a form of construction of a type casting and composing machine shown by way of example on the accompanying drawing, wherein:—

45 Fig. 1 is a front elevation of the casting mould and of the driving mechanism, the front wall of the mould being removed.

Fig. 2 shows in side elevation a typeless invariable matrix head.

50 Fig. 3 shows in side elevation a typeless variable matrix head for the casting of the spacers to be inserted instead of the provisional spacers.

Fig. 4 is a side elevation of Fig. 3.

55 Fig. 5 shows in side elevation a matrix head with two types.

Fig. 6 shows the machine in side elevation, partly in section.

Fig. 7 illustrates the line pusher.

Fig. 8 shows the back wall of the casting 60 mould with injecting orifice in which a knife is mounted which is designed to cut off the burr.

Fig. 9 shows in plan view the casting mould with the line collecting channel, the 65 justifying carriage, the pusher, the bearing for the matrix levers and the line transporter.

Fig. 10 shows in elevation the rear wall 70 of the line-collecting channel.

Fig. 11 shows the return slide for the line.

Fig. 12 shows the wall of the type collecting channel with the opening in front of the 75 justifying carriage.

Fig. 13 shows part of the two side walls with the carriage for the matrix levers.

Fig. 14 shows the type shifter in the type collecting channel.

Fig. 15 illustrates a provisional spacer 80 with justifying slide.

Fig. 16 shows the centering rod with the matrix.

The construction and the operation of the machine shown in general as well as in detail are as follows:—

By the depression of key 1 (Fig. 6) which is pivotally mounted upon a continuous transverse rod 2 a pull rod 4 is operated by arm 3, said pull rod 4 being coupled with an arm 6 mounted upon a second transverse rod 5; arm 6 rests upon a beam 7. Upon this arm 6 a rod 9 held by a spring 8 is loosely mounted, said rod 9 being connected with the matrix lever 10 pivotally mounted 95 at 11 and designed to throw the matrix head 11^a (Figs. 5, 6) of this arm 10 upon the casting mould. The matrix lever 10 strikes with its point 12 (Figs. 5, 6) upon the elastic insertion 13 (for instance of hard rubber) of the operating lever 14 for the casting mechanism (Figs. 1 and 9). This operating lever 14 (Figs. 1, 9) in striking upon the casting mould slips under the flap 16, and the spring controlled measuring 105 rail 17, in which lever 14 is mounted, looses thus its hold. The vertical arm 18 of rail 17 jams the matrix by pressing it against the second jaw. The matrix lever rests at 13 upon the operating lever 14 for the casting mechanism. Upon the measuring rail 17 a roller 20 is mounted (Fig. 1) with

which an arm 21 is in contact which is keyed upon the shaft 23 (Figs. 1 and 6). From shaft 23 an arm 24 extends upwards and as arm 21 (Fig. 1) looses its hold in consequence of the yielding of roller 20 supported by the measuring rail 17 this movement is transmitted also to arm 24 and transferred by means of rod 25 upon the angle lever 26, 28 fulcrumed at 27 and consequently upon the pump rod 29 and pump piston 30 (Figs. 1, 6, 9). The metal 31 below the pump piston 30 is driven through channel 32 (Figs. 6 and 9) and through the orifice 33 (Fig. 8) into the type chamber 34 covered by the jammed matrix (Figs. 1, 6, 9). Between channel 32 and orifice 33, Fig. 6, a space 33' is arranged which is designed to receive the metal cut off at two sides of the cast type and to conduct this metal to a collecting chamber.

During the casting of a type or of a spacer another operation has taken place. Upon shaft 23 (Figs. 1, 6) an arm 35 is keyed which by the action of a spring 36 has brought an eccentrically mounted toothed wheel 37 in gear with a second continuously revolving toothed wheel 38. As the eccentrically mounted toothed wheel 37 causes the back movement of arm 35 and of the arms 21 and 24 mounted upon shaft 23 in order to lift the piston of the casting pump and to eject the cast type from the mould, the following movements take place: The depressed operating lever 14 for the casting mechanism (Fig. 1) has moved towards arm 21 a roller 40 mounted upon shaft 39 by a lever and this roller 40 has communicated its movement by the intermediary of pins 41, 42 (Figs. 1, 16) to the centering rod 43 for the matrix which traverses the clamping device 18 (Figs. 1 and 9), said rod having centered the matrix by engaging with one of the centering holes 44 (Figs. 2, 3, 5, 6, 16) and it participates now first in the return movement, arm 14 lifting at the same time the matrix off the cast type in the casting chamber through the intermediary of the lever 10. The arm 21 acts further upon the roller 46 of a rail 45 the arm 47 of which pulls the cast type from the mould at which occasion the burr in the orifice 33 (Fig. 8) is cut off by the knife 50. As the matrix is not fixed upon the casting mould but upon lever 14 burrs have been formed also at the points of the matrix which have not been clamped and these burrs are removed by knives 48, 49 (Fig. 9) arranged upon the two jaws of the casting mould.

The shaft of the eccentric toothed wheel 37 (Fig. 1) has in the meantime been pushed to the end of the travel and the cast type in chamber 34 has arrived opposite the ejecting channel 51. With the eccentric toothed wheel 37 (Figs. 1, 9) a roller 52 has moved

which is mounted upon the rear side of said toothed wheel by means of a lever arm and this pulley has advanced a slide 53. Two stops 54, 55 upon slide 53 have drawn along an arm 56 keyed upon shaft 57. Upon this shaft an arm 58 is further keyed which has transferred the movement of the shaft to the type ejector 59. This type ejector 59 is therefore operated from slide 53. A traction element 60 is attached to the slide 53 (Figs. 1 and 14). The other end of this traction element 60 is attached to a two-armed lever 61 which pulls thus back the type slide 62 with the ejectors 63, 64 (Figs. 9, 14) so that the type ejector 59 can bring the cast type into the type collecting channel 65.

As the shaft of the eccentric toothed wheel having exceeded its greatest distance from the driving wheel moves towards the initial position shown on the drawings all the elements operated by arm 21 (Fig. 1) return to the initial positions so that the operating lever 14 for the casting mechanism comes with its point in contact with the flap 16 which supports the same until it is deprived again of its support by the depression of another key so that another type or spacer is cast.

Suppose the following phrase had to be typed: "Durch diese hohle Gasse muss er kommen" and this phrase could be set in the space of one line with the exception of the last character "n" and the full stop so that the provisional spacing between the words would have to be shortened accordingly. In the collecting channel 65 the characters D, u, r, c for the word "Durch" are already set. If now the last character "h" for the word "Durch" has been typed and cast the first spacer has to be inserted. With this object in view the key 66 is depressed so that, by means of an arm 67 the movement is transmitted to a curved rail 68 (Fig. 6). This curved rail 68 engages with a tooth 69 of the justifying slide 71 (Figs. 6, 9, 15) and shifts this slide for the thickness of the provisional spacer 70 whereby this spacer is inserted between the pushers 63, 64 (Fig. 14) through the opening 72 of the front wall 73 of the type collecting channel (Fig. 12) behind the "h" of the word "Durch". By the same depression of key 66 (Fig. 6) a downwardly projecting suspended arm 74 has further been operated which is however prevented by rod 75 to catch with its hook 76 the stud 77. By this depression of the spacing key 66 only a provisional spacer is inserted into the line which is being composed but the casting mechanism is not operated. The next following word "diese" is now typed and the second spacer is inserted, whereupon the word "hohle" and the third spacer, and the word "Gasse" and the fourth and last provisional spacer are typed. The justifying slide 71 has thus been moved for the

length of the four spacers 70 and a catch 78 has drawn along arm 79 with the horizontal rod 75 (Fig. 6) wherefrom results that the hook 76 of the suspended arm 74 comes in engagement with the stud 77 and, after the word "muss" has been typed, a typeless matrix is brought upon the casting mould by the following depression of key 66 so that a spacer is cast. The same takes place for the further intervals between the words.

The line is now overfull with the phrase which has thus been composed. The transfer of this freshly composed line into the galley 80 (Fig. 9) is now initiated by the depression of the hand lever 81 (Fig. 7) which is arranged at the right hand side of the key board. A pull rod 82 (Figs. 7, 9) draws along the upright arm 84 upon shaft 83 together with the type pusher 85. The two plates 86, 87 of this type pusher 85 advance through the openings 88, 89 of the back wall 90 of the line collecting channel (Fig. 10) and push the line which has been collected in this channel 65 into the galley 80, the front wall 91 of the type collecting channel having been lowered at the same time with the aid of levers 92, 93 arranged upon shaft 83. The hand lever 81 returns under the action of spring 94 immediately into its initial position, same as the type pusher 85. The type pusher 85 has, by means of the abutment 95 arranged at its rear end, drawn along the arm 96 fulcrumed at 97 and displaced through the intermediary of arm 98 and the traction rod 99 the line conveyor 100 with traction hook 101 in such a manner that the traction hook gets close to the type ejecting channel without however obstructing the same. As the collecting channel 65 has been emptied in consequence of the line having been transferred to the galley 80 the stop 102 has been pulled forward through the intermediary of a weighted pull rope 104 attached to the nose 103 of abutment 102 so that the types of the freshly composed line are prevented from tumbling. The projection 105 of pull rod 82 has further drawn along a lever arm 106 which, by means of rail 107, has stopped the line conveyor 100 with nose 108 (Fig. 9), a second arm 109 which is mounted approximately at right angles with regard to the arm 106 having pulled back the type slide 62. A traction element 111 of arm 109 has drawn along the justifying carriage 112. This justifying carriage 112 has operated by means of its arm 114 another arm 110 pivotally mounted at 113 so that the type pushers 63, 65 (Figs. 9, 14) have been withdrawn from the line collecting channel. The justifying carriage 112 (Fig. 9) is held in its position by the spring influenced catch hook 115 engaging with the notch 116 of the carriage. A traction element 117 of the carriage 112 causes the outer end of the

angle lever 118 to disengage from the teeth of the line return slide 119 (Figs. 9, 11) which now, by a weighted rope 120, is moved back together with the composed line until the fourth provisional spacer which has been inserted after the word "Gasse" strikes with its nose 131 (Fig. 15) against point 122 of the front wall 73 of the type collecting channel. The provisional spacer stands now between the type ejecting channel 51 and the orifice of the collecting channel for the provisional spacers. As the carriage 112 has been displaced slightly towards the right hand side this registering has been effected. At this instant the justifying key is depressed which is loosely connected with a matrix lever 10 provided with a variable typeless head (Figs. 3 and 4). The head can be varied or modified owing to the arrangement that two adjustable wedges 123, 124 are adapted to be moved according to requirement, which is effected in the following manner.

Upon the type returning slide 119 an adjustable pin 125 (Figs. 9, 11) limiting the length of the line, is arranged. If the line exceeds the admissible length this stud draws along the arm 126 which movement is transferred by rod 127 upon the movable measuring plate 128. The movable measuring plate 128 has bevelled noses 129 (Figs. 3, 9). The number of noses corresponds with the number of characters mounted upon the several levers 90. The measuring plate has thus been adjusted for the desired length of line. If now the variable typeless head (Figs. 3, 4) of lever 10 is lowered upon the casting mould the feeling hammer 129 (Figs. 3, 4) is moved, when coming in contact with the bevelled nose 129, and the wedge 123 is adjusted so that as soon as the two jaws 18, 19 come together a definite casting piece for the spacer is produced which shortens the line.

This definite cast piece is inserted in the line in the same manner as the types are inserted and it drives the provisional spacer out of the line into the magazine of carriage 112. The line is shifted immediately for the length of the word "Gasse" and the next following provisional spacer is replaced by a definite cast piece and so on until definite spacers have been substituted for all four provisional spacers. As soon as the fourth provisional spacer 70 (Figs. 6, 15) has been brought back to its proper place, an abutment 130 has pushed back the lever 79 and the rod 75 has brought the hook 76 of the suspended arm 74 out of engagement with stud 77. Upon the type return slide 116 another fixed stud 131 is arranged which serves for returning the measuring plate 128 to the initial position. The releasing stud 132 which is also mounted upon the type return slide 119 pulls back the lever 130

arm 133 and the nose 115 comes out of engagement with 126 so that the justifying carriage 112, the two type pushers 63, 64 with slide 62, and also rail 107 with nose 108 return into the initial positions shown on the drawing whereby the type conveyor 100 is released and pulls in front of the galley 80 by means of its lock under the action of the weighted rope 134 the line which 19 has just been composed.

If now in the phrase cited by way of example the word "muss" should be printed in special type the segment block 135 (Figs. 9, 13) could be shifted by means of a reversing key, the carriage 136 (which has been shown on the drawings only at one side of the machine) being moved by the traction element 137 (Fig. 13) from the key board. The segment block 135 with the matrix levers could be eventually lifted off the carriage 136 and exchanged as the individual matrix levers 10 are not connected with the key board by a continuous rod and lever system.

23 I claim:—

1. Type casting and composing machine for the production of justified lines composed of individual types comprising in combination oscillable levers to be operated by the depression of keys, matrices on the ends of said levers, a common casting mould designed to receive the matrix of the depressed lever which matrix forms then the lid of said mould, a line channel, a device for conducting the cast types into said line channel, a device for conducting a limited number of provisional spacers (for instance five) of equal thickness into said line channel, a device for ejecting the provisional spacers from the composed line, and a device for substituting definite cast spacers for said provisional spacers during the transfer of the line to the galley.

2. Type casting and composing machine for the production of justified lines composed of individual types comprising in combination oscillable levers to be operated directly by the depression of keys, matrices on the ends of said levers, a common casting mould designed to receive the matrix of the depressed lever which matrix forms then the lid of said mould, a movable part

of said mould consisting of two jaws having each an extension designed to clamp the matrix from the sides.

55

3. Type casting and composing machine for the production of justified lines composed of individual types comprising in combination oscillable levers to be operated directly by the depression of keys, matrices on the ends of said levers, a common casting mould designed to receive the matrix of the depressed lever which matrix forms then the lid of said mould, a rod for centering the matrices and means for horizontally guiding said rod.

4. In a type casting and composing machine of the type described the matrix levers which, similar to the type levers of typewriting machines, can be reversed in order to bring the different type-matrices into the casting position.

5. In a type casting and composing machine of the type described a nonmetallic insertion in the operating lever for the casting mechanism upon which the matrix lever strikes if it brings the matrix to the casting mould.

6. In a type casting and composing machine of the type described in combination with the matrix and with the casting mould, a measuring rail, a jaw of said rail, and a rod in said jaw for centering by its points the matrix upon the casting mould and a second jaw for jamming the matrix between said two jaws.

7. In a type casting and composing machine of the type described the arrangement, that if the provisional spacers have been pushed back into the magazine, a typeless matrix lever, which has entered in function as the provisional spacers had been replaced, is thrown out of gear.

8. In a type casting and composing machine of the type described the arrangement that all matrix levers rest each by means of a transverse rod upon arms operated from the keys but are not connected with said arms in order to ensure a rapid changing of the types by exchanging the matrix lever mechanism.

In testimony whereof I affix my signature.

NIKLAUS MEIER.
